UNITED STATES PATENT OFFICE.

RICHARD M. BEDELL, OF BROOKLYN, NEW YORK, ASSIGNOR TO MERGENTHALER LINOTYPE COMPANY, A CORPORATION OF NEW YORK.

TYPOGRAPHIC MACHINE.

1,076,184.

Specification of Letters Patent. Patented Oct. 21, 1913.

Application filed July 15, 1911. Serial No. 638,611.

To all whom it may concern:

Be it known that I, RICHARD M. BEDELL, a citizen of the United States, and a resident of Brooklyn, county of Kings, and State of

5 New York, have invented a new and useful Improvement in Typographic Machines, of which the following is a specification.

My invention relates generally to typographical composing machines, and more 10 particularly to line casting machines, such as are well known to the public under the name "Linotype," and as presented for instance in the U. S. Letters Patent to J. R. Rogers, No. 848,771, and No. 930,693.

15 I have shown my improvements as incorporated in a machine substantially or in many respects like that illustrated in the said Letters Patent, and it is to be understood that as to all features not shown or 20 described, they may be identical therewith, or with any other similar construction. In each of these said patents a series of magazines is employed in order that matter of variant faces may be composed in the manner 25 well known in the art, by a proper selection of the several fonts therein contained. It is also common and well known to provide means whereby the individual magazines of such a series may be removed and 30 replaced by others in order still further to diversify the characters or faces.

35 My present invention relates to means whereby these individual magazines may be conveniently and readily mounted in operative position, and when desired may be easily interchanged for others in the manner previously referred to.

To this end, and more specifically, I prefer to mount each magazine upon individual 40 supporting means, and to employ in connection therewith a locking device which maintains the magazine in position thereon, and which when unlocked permits the removal of the magazine in its normal plane. Ordinarily and in the linotype referred to, the 45 individual magazines are mounted in an inclined position and rest at their forward ends upon a cross bar connected to the main frame. Upon this cross bar the locking device 50 is preferably mounted and may be moved into operative or inoperative position at will. When the parts are unlocked, the magazine may be slid forwardly and downwardly over the supporting bar in its normal 55 plane, this action being assisted by grav-

ity, due to the inclination of the magazine. After its removal another magazine may be substituted therefor by reversing the operation just described.

The ability to remove the magazine in its 60 normal plane is of great importance, and principally for the reason that in many previous arrangements it has been necessary to lift it from its ordinary position before removal. Thus for instance, in one type of 65 machine it was customary to superimpose the magazines one upon another, and in order that they might be held in proper relation, they were provided respectively with projections and sockets which held them securely in place. In another form, the inclined magazines were individually mounted upon supporting frames and were held in proper position thereon by ledges or projections on the frames. In both of these 70 cases it is necessary to elevate the magazine in order to free or clear it, and before it can be removed from the machine. Such manipulation is entirely obviated by the arrangement herein set forth, and wherein 75 when the magazine is disconnected from its support by a proper operation of the locking device, it may be slid thereover and removed in the manner hereinafter more specifically to be described. I am also aware 80 that it is old in the art to remove magazines laterally and substantially in their normal planes, and I lay no claim to such an arrangement in the present case, which more 85 specifically contemplated their removal downwardly and in their normal planes.

In the accompanying drawings I have 90 illustrated one embodiment of my invention, but it will be obvious that many changes and 95 variations may be made therein without departing from its spirit; and generally speaking, I desire to be understood that I do not limit myself to any specific form or embodiment except in so far as such limitations are 100 specified in the claims.

Referring to the drawings: Figure 1 is a 105 perspective view, partly broken away, of sufficient of a linotype machine to illustrate the application of my invention thereto; Fig. 2 is an enlarged sectional view taken substantially on the line 2-2 of Fig. 1; Fig. 3 is an enlarged sectional detail view taken substantially on the line 3-3 of Fig. 4; and Fig. 4 is a perspective view of the magazine 110

and its supporting bar dissociated, giving a bottom view of the former and a plan view of the latter.

Referring to the drawings, Fig. 1 illustrates a portion of a linotype machine such as is shown in the Rogers Patent, No. 930,693, previously referred to, and wherein the front frame or plate D swings about a vertical pivot in order to give access to the interior parts. Any number of magazines may be employed in connection therewith, although for present purposes only one, A, is more particularly described. Its central and rear portions may be supported in any desired manner, such for instance as in the patents previously mentioned, although at its front end it is herein shown as resting upon the cross bar B suitably mounted in the main frame E. The magazine A is provided with the brace A¹, which normally enters and rests in the transverse slot B¹ formed in the bar B (see Fig. 1). The magazine is preferably mounted in inclined position, as in the patents above referred to, and in order to hold it in relation to the supporting bar B, the latter is provided with the locking piece C, which is slidably mounted in the groove B² formed in said bar. In order to hold the piece C firmly in operative position, the groove B² is preferably formed with an under cut or dovetail B³ (see Fig. 3), and the slide C is similarly shaped, holding pieces B⁴, B⁴, being employed to insure the correct relations of the parts. The slide C is provided with a handle C¹, whereby it may be moved across the slot B¹ so as to engage the brace A¹ of the magazine A, as shown in Figs. 1 and 2, thereby holding the magazine in place, or so as to clear the slot B¹, as shown in Fig. 4. In the latter condition of the parts, the magazine A may be slid forwardly over the bar B in its normal plane, and another magazine may be substituted therefor, after which the slide C is again returned to its normal or locking position. It will be understood, of course, that the frame D will be swung outward during this change of magazine, in the manner indicated in the Rogers Patent, No. 930,693.

Having thus described my invention, its construction and mode of operation, what I claim and desire to secure by Letters Patent of the United States, is as follows:

55 1. The combination of a magazine and supporting means therefor, with a movable locking device to support the magazine in normal position thereon and which when moved permits the forward removal of the magazine in its normal plane.

2. The combination of an inclined magazine and supporting means therefor, with a movable locking device to support the magazine in its inclined normal position thereon and which when moved permits the

downward removal of the magazine in its normal plane.

3. The combination of a magazine and supporting means therefor, with a movable locking device to support the magazine in normal position thereon and which when moved permits the forward removal of the magazine in its normal plane and from the said supporting means.

4. In combination, a magazine, the main frame, and a bar to support the magazine, together with a movable locking device to support the magazine in normal relation to the bar, and which when moved permits the forward removal of the magazine in its normal plane.

5. In combination, a magazine, the main frame, and a bar to support the magazine, together with a movable locking device to support the magazine in normal relation to the bar, and which when moved permits the removal of the magazine in its normal plane and over the said bar.

6. In combination, a magazine, the main frame, and a support for the magazine, together with a locking device mounted upon the said support and adapted to hold the magazine in normal relation thereto, and which when unlocked permits the removal of the magazine in its normal plane.

7. In combination, a magazine, the main frame, and a bar to support the magazine, together with a locking device mounted upon the said bar and adapted to hold the magazine in normal relation thereto, and which when unlocked permits the removal of the magazine in its normal plane and over the said bar.

8. In combination, a magazine, the main frame, and a support for the magazine, together with a locking device slidably mounted upon the said support and adapted to sustain the magazine in normal relation thereto, and which when slid to its unlocking position permits the removal of the magazine.

9. In a linotype machine, the combination of a magazine, a supporting bar therefor, and a locking device slidably mounted in a groove in said bar to hold the magazine in its normal position, and which when slid to its unlocking position permits the removal of the magazine.

10. In a linotype machine, the combination with the magazine A provided with a piece A¹, of a bar B formed with the notch B¹ to receive the piece A¹, and with the groove B², and the locking piece C slidably mounted in said groove.

11. In a linotype machine, the combination of the magazine A, the bar B to support the magazine and having the dove-tail groove B², the locking slide C mounted in said dove-tail groove, and the piece B⁴ to hold the locking slide in position.

12. The combination of a supporting frame, a magazine supported thereon in an inclined position and adapted to slide outwardly by gravity, and a movable stop device serving to check the outward movement of the magazine, said movable stop device being adapted to be withdrawn and thus to release the magazine.

In testimony whereof I hereunto set my hand this fourteenth day of July, 1911, in the presence of two attesting witnesses.

RICHARD M. BEDELL.
